UNITED STATES PATENT OFFICE.

CALDER C. GIBSON, OF BUFFALO, NEW YORK.

CUTTING AND STAMPING MACHINE.

Application filed May 13, 1921. Serial No. 469,328.

To all whom it may concern:

Be it known that I, CALDER C. GIBSON, a citizen of the United States, residing at Buffalo, in the county of Erie and State of New York, have invented new and useful Improvements in Cutting and Stamping Machines, of which the following is a specification.

This invention relates to a cutting and stamping machine by which the stub or portion of a gas bill, invoice or other paper is severed or cut from the remaining portion and at the same time a date or other matter printed on both the main and stub portions of the bill or other paper.

A machine of this kind is shown and described in Letters Patent of the United States No. 1,038,741, granted to me September 17, 1912.

One of the objects of the invention is to provide the machine with simple means for reversing the type-holding device to a convenient and accessible position, in order to facilitate changing the type, when required.

Another object is to provide the machine with an improved inking pad which can be manipulated without soiling the hands.

In the accompanying drawings:

Figure 1 is a side elevation of the machine, showing the parts in their normal position by full lines and in their cutting and printing position by dotted lines. Figure 2 is a top plan view thereof. Figure 3 is a fragmentary longitudinal section on line 3-3, Fig. 2, showing the parts in their normal position by full lines and in their inking position by dotted lines. Figure 4 is a fragmentary transverse section on line 4-4, Fig. 1. Figure 5 is an enlarged fragmentary horizontal section, on line 5-5, Fig. 4. Figure 6 is a fragmentary vertical section on line 6-6, Fig. 5. Figure 7 is a perspective view of the printing block. Figure 8 is a fragmentary side elevation of the machine, showing the printing block in its reversed position for changing the type. Figure 9 is a fragmentary front view of the machine with the parts in the position shown in Fig. 8. Figure 10 is a fragmentary transverse section on line 10-10, Fig. 8, on an enlarged scale. Figure 11 is a longitudinal section on line 11-11, Fig. 10.

Similar characters of reference indicate corresponding parts throughout the several views.

In the embodiment of the invention illustrated in the drawings, the printing and cutting mechanisms are mounted on a comparatively small box-like cabinet 15 having a removable drawer 16 for receiving the severed portions of the bills or other papers. The top 17 of this cabinet forms a bed or table for the bills to be printed and is provided with a longitudinal slot 18 for receiving the cutter mechanism and an opening 19 for the passage of the severed stubs into the drawer below.

The cutter mechanism may be of any suitable construction, being preferably composed of a stationary cutter-blade 20 suitably secured to one of the walls of the slot 18 and a vertically-movable knife or cutter blade 21 pivoted at 22 to a base block 23 mounted on the rear portion of the cabinet 15. A spring 24 attached at one end to the movable cutter and at its other end to the rear wall of the cabinet serves to normally maintain the cutter in its elevated or inoperative position, as shown by full lines in Figs. 1, 3 and 8.

The printing mechanism is disposed above the top of the cabinet and is preferably constructed as follows:

The frame for supporting the printing mechanism comprises a pair of side plates or standards 25, 25, which are suitably secured to the base block 23 and between which is mounted a removable ink pad 26 of any appropriate form. Pivoted or fulcrumed at the upper front ends of these plates is a vertically-swinging U-shaped operating member or lever 27 carrying between its arms a pendant type-holding device which includes a frame or carrier 28 and a type-supporting block 30. The end ears 28^a of this carrier are connected centrally to the arms of the operating lever 27 by pivot pins 29 arranged transversely of the machine. The type-supporting block 30 is arranged on the bottom of the carrier 28 and is provided in its underside with a recess 31, the bottom of which is metal-lined and adapted to contact with the upper edge of the movable cutter blade 21 to depress it when the operating lever is swung forwardly and downwardly to printing position, shown by dotted lines in Fig. 1. In order to facilitate the removal of the type block from its carrier 28, it may be provided on its upper side with a pair of

spring clips 32, 32, whose hooked ends embrace the front and rear edges of said carrier, as shown in Figs. 3 and 7.

Secured to the lower side of the supporting block 30 are two type holders 33, 33, preferably of rectangular form in which are removably arranged the printing type or stamps 34 for imprinting the date or other desired matter on the bills or other papers. The type may be formed of rubber, and frictionally held in the bed 35 carried by each holder, as shown in Figs. 10 and 11.

In order to maintain the carrier 28 and its block 30 in a substantially level position when swung to printing or inking position, parallel links 36, 37 are provided which connect said carrier with the fixed side plates 25, as shown in Figs. 1 and 3. One of these links, say the link 36 at the right hand side 20 of the machine, is preferably permanently pivoted at one end to the corresponding plate 25 and at its other end to the adjacent ear 28^a of the carrier, as shown at 38 and 39, respectively. This right-hand link is disposed below and parallel with the arms of the operating lever 27 and the pivots of said links are substantially in vertical alinement with the respective pivots of the operating lever and the carrier, as clearly shown in Fig. 3, 30 said link being thus pivoted centrally to the adjacent ear 28^a. One end of the link 37 on the left-hand side of the machine may be permanently pivoted at 40 to the corresponding plate 25, while its other end is detachably connected to a spring-pressed pivot and coupling pin 41 guided for horizontal movement in bearings 42 and 43 in the adjacent upper rear side of the carrier 28, as shown in Fig. 5. A spring 44 arranged in the bearing 43 normally tends to move the pivot pin outward into engagement with an opening 46 in the link 37, this pin having a knurled collar 45 for withdrawing it from said opening. This collar is arranged between its 45 bearings and also performs the function of limiting the movement of the pivot pin in either direction. Said link 37 is also disposed below and parallel with the arms of the operating lever, the pivot 40 of said link 50 being preferably behind the plane of the corresponding pivot of the link 36, while the pivot pin 41 thereof is behind the plane of the corresponding pivot 39 of said link 36.

By this arrangement when both links 36 and 37 are in their operative position, the carrier 28 together with its type block is always maintained in a substantially level position as the operating lever 27 is swung to printing and inking positions, as shown in Figs. 1 and 3, respectively.

When it is desired to move the carrier and its type supporting block to the reversed position shown by full lines in Fig. 8, the link 37, which functions to normally keep said elements in an upright position, is discon-

nected from the carrier by withdrawing the pivot pin 41 from said link, as shown by dotted lines in Fig. 5, and allowing it to drop to the position shown in said figure. The operating lever is then moved upwardly and rearwardly from its normal position shown by full lines in Figs. 1 and 3 to the position shown by dotted lines in Fig. 8, the block and carrier being at the same time swung backward by hand on the operating lever. In this position of the parts the pivot 39 of the permanently-connected link 36 is located behind the dead center line drawn through the other pivot 38 of said link and the corresponding pivot pin 29. Upon now 80 swinging the operating lever forwardly and downwardly, the carrier together with its block is turned rearwardly and upwardly and thence forwardly about the upper pivot 39 of the link 36 as a fulcrum, completely 85 reversing the carrier and its block to the position shown by full lines in Fig. 8, by the time that the handle of operating lever comes in contact with the top of the cabinet. In this inverted position of the block 90 type 34 can be conveniently and quickly changed. The type block is inverted to this accessible position by simply swinging the operating lever first backward and then forward, thus doing away with the necessity of 95 removing the type block from the carrier 28 and again replacing it to change the type, saving considerable time and increasing the convenience of the machine.

To reset the parts for normal operation, the 100 operating lever is swung upwardly and rearwardly, to return the carrier and its block to the upright position shown by dotted lines in Fig. 8, whereupon the link 37 is again coupled to the carrier by the pivot pin 41, 105 thus restoring the machine to its normal condition for stamping and clipping bills, etc.

The ink pad 26 is preferably secured in a sheet metal holder having a bottom 47 and upright longitudinal handle-flanges 48 which 110 extend a suitable distance above the inking surface of the pad, as shown in Fig. 3. The holder rests upon corner seats 49, preferably cast on the standards 25, and is confined between lugs or flanges 50 projecting upwardly 115 from the outer edges of said seats. The flanges 48 form convenient means for grasping the holder in putting it in place and removing it; said flanges by projecting above the surface of the pad, preventing the hands 120 from touching it and becoming soiled.

I claim as my invention:

1. A machine of the character described, comprising a frame, an operating member mounted on said frame, a type-holding device carried by said operating member and capable of reversal thereon, and means for connecting said typeholding device with said frame to normally maintain it in a substantially level operative position during the 130

movements of said operating member, said connecting means including a part detachable from said typeholding device and the remaining parts of said connecting means 5 being arranged to move the typeholding device out of its operative position by the action of said operating member, to facilitate access to the type of said holding device.

2. A machine of the character described, 10 comprising a frame, an operating member mounted on said frame, a movable typeholding device actuated by said member, detachable means for connecting said type holding device with said frame to normally maintain 15 said device in a substantially level operative position, and additional connecting means between said typeholding device and said frame to cause the reversal of said device by the action of said operating member 20 when said first-named connecting means are detached.

3. A machine of the character described, 25 comprising a frame, an operating lever fulcrumed on said frame, a reversible typeholding device carried by said lever, and means for connecting said typeholding device with said frame to normally maintain it in a substantially level position during the movements of said lever, a part of said connecting means being detachable from said typeholding device to permit the latter to move to reverse position upon the downward movement of said operating lever.

4. A machine of the character described, 35 comprising a frame, an operating lever fulcrumed on said frame, a reversible typeholding device pivotally mounted on said lever, and links pivotally connecting said typeholding device with said frame to normally maintain it in a substantially level position during the movements of said lever, one of said links being detachable from said typeholding device, and the other being pivoted to swing rearwardly beyond the 45 dead center when said lever is swung in that direction, the upper pivot of the last-named link acting as a fulcrum on which said carrier turns to its reversed position when said lever is swung forwardly.

5. A machine of the character described, 50 comprising a frame, an operating lever pivoted to said frame, a typeholding device pivotally suspended from said lever, and a pair of parallel links pivotally connected at

their ends to said typeholding device and 55 said frame, respectively, the pivots of one of said links being in substantially vertical alinement with the pivots of said typeholding device and said lever, while the pivots of the other link are out of vertical alinement 60 with the pivots of said typeholding device and said lever.

6. A machine of the character described, 65 comprising a frame, an operating lever pivoted to said frame, a typeholding device pivotally suspended from said lever, and a pair of parallel links pivotally connected at their ends to said typeholding device and said frame, respectively, the pivots of one of said links being in substantially vertical 70 alinement with the pivots of said typeholding device and said lever, while the pivots of the other link are out of vertical alinement with the pivots of said typeholding device and said lever, said last-named link 75 being detachably connected with said typeholding device.

7. A machine of the character described, 80 comprising a frame, a vertically-swinging operating lever pivoted to said frame, a typeholding device pivotally suspended from said lever, a pair of parallel links pivotally connected at their ends to said typeholding device and said frame, respectively, the pivots of one of said links being in substantially vertical alinement with the pivots of said typeholding device and said lever, while the pivots of the other link are out 85 of vertical alinement with the pivots of said typeholding device and said lever, and a spring-pressed pivot pin mounted on said typeholding device for detachably connecting said last-named link thereto.

8. A machine of the character described, 95 comprising a frame, an operating lever fulcrumed on said frame, a reversible typeholding device pivotally mounted on said lever, detachable means for normally retaining said typeholding device in its stamping position during the movements of said lever, 100 and a link pivoted at one end to said frame and having its other end pivoted to the central portion of said typeholding device to cause reversal of the latter by the forward movement of said lever when said retaining 105 means are detached.

CALDER C. GIBSON.
